UNITED STATES PATENT OFFICE.

PORTER S. HAMRICK, OF WAUSAU, WISCONSIN.

COCK AND FAUCET.

1,027,474.

Specification of Letters Patent.

Patented May 28, 1912.

Application filed February 17, 1912. Serial No. 678,205.

To all whom it may concern:

Be it known that I, PORTER S. HAMRICK, a citizen of the United States, residing at Wausau, in the county of Marathon and State of Wisconsin, have invented certain new and useful Improvements in Cocks and Faucets, of which the following is a specification, reference being had to the accompanying drawings.

10 This invention comprehends certain new and useful improvements in cocks and faucets, and relates particularly to an improved combined fixture which will possess all the necessary requisites or characteristics of a 15 basin faucet and drinking fountain.

The invention has for its primary object a simple and efficient fixture of this character the parts of which are so constructed and arranged that the device may be used 20 on an ordinary dispensing faucet for a wash basin or the like, and may also, when manipulated as will be hereinafter fully described, serve as a sanitary drinking fountain, the fixture being thereby especially 25 valuable for use in school rooms, railway stations, or similar public or quasipublic places.

A further object of the invention is a device of this character the parts of which 30 may be easily manufactured and readily assembled and disassembled, should it become necessary to repair any of them. And the invention also aims to generally improve this class of devices and to render them 35 more useful and commercially desirable.

With these and other objects in view as will more fully appear as the description proceeds, the invention consists in certain constructions, arrangements and combinations of the parts that I shall hereinafter 40 fully describe and claim.

For a full understanding of the invention reference is to be had to the following description and accompanying drawings, in 45 which:

Figure 1 is a vertical sectional view of a combined faucet embodying the improvements of my present invention, parts being shown in side elevation; and Fig. 2 is a section on the line 2-2 of Fig. 1.

Corresponding and like parts are referred to in the following description and designated in the accompanying drawing by like reference characters.

50 My improved combined fixture includes a faucet 1 which is provided with any desired

form of valve, such as that indicated at 2, controlling the passage of water to the longitudinal spout or bore 3. The bore of the spout 3 is intersected at its discharge end 60 by a vertically disposed cylindrical passage 4 open throughout its extent and at both ends, and in said passage there is mounted for rotation the preferably reduced lower end of the curved tubular arm 5 the lower 65 extremity of said arm, where it protrudes downwardly from the passage 4, being exteriorly threaded as indicated at 6 to receive the retaining nut 7, as clearly illustrated in Fig. 1. The arm 5 is formed with 70 a downwardly facing annular shoulder 8 which is adapted to bear upon the upper side of the spout 3 around the upper end of the passage 4.

The tubular arm 5 is formed within the 75 passage 4, with a preferably obliquely disposed partition 9 extending thereacross and in its side walls with a port 10 below said partition and with a port 11 above said partition. Preferably the ports 10 and 11 are 80 disposed in diametrical relation to each other and the port 11 is preferably smaller than the port 10. The arm 5 is open from the partition 9 downward so as to form a discharge mouth 12. The upper end of the 85 tubular arm 5 carries a bulbous head 5^a which serves as the mouth piece of the drinking fountain and which is specifically described and claimed in my co-pending application for Letters Patent of the United 90 States, Serial No. 670,029, filed on or about the 8th day of January 1912.

From the foregoing description in connection with the accompanying drawing the 95 operation of my improved combination fixture, will be apparent. In the practical use of the device, when it is desired to use the fixture as an ordinary basin faucet, or the like the arm 5 is turned to the position shown in dotted lines in Fig. 1, when, as 100 will be evident, the relatively large port 10 will register with the bore of the spout 3 and hence upon the opening of the faucet by turning the handle of the valve 2 the water will flow freely through the bore 3 105 and registering port 10 and outwardly through the downwardly facing discharge mouth 12. When it is desired to use the device as a drinking fountain, it is only necessary to turn the arm to the full line position illustrated in Fig. 1, whereupon the 110 relatively small port 11 will register with

the bore of the spout 3 and the water will pass upwardly through the tubular arm and out through the head or mouth piece 5^a. Thus it will be seen that I have provided a 5 very simple and efficient device, the parts of which may be easily assembled and disassembled and which will not be liable to get out of order or require any unnecessary attention.

10 The arm 5 may be easily detached from the spout 3 by merely unscrewing the nut 7. While the accompanying drawing illustrates what I believe to be the preferred embodiment of my invention it is to be understood that the invention is not limited thereto but that various changes may be made in the construction, arrangement and proportion of the parts without departing from the scope of the invention as defined 15 in the appended claims.

Having now fully described my invention what I claim is:

1. A combination fixture of the character described including a faucet provided with 25 a spout having a longitudinal bore and a vertically disposed passage intersecting said bore, and a drinking fountain embodying a tubular arm mounted for a turning movement in said passage, and formed therein 30 in registry with the outlet end of the bore,

with an oblique partition, the arm being formed below the partition with a relatively large port and above the partition with a relatively small port, both of said ports being adapted to register alternately with the 35 bore, the arm being open from the partition downward.

2. A combination fixture of the character described, including a faucet provided with a spout having a longitudinal bore and a 40 vertical passage intersecting the bore at the discharge end of the latter, and a drinking fountain embodying a tubular arm mounted for a turning movement in said passage, the lower extremity of said arm protruding 45 from the lower end of the passage and formed with exterior screw threads, and a nut screwed thereon and engaging the lower side of the spout, the arm being formed with a shoulder bearing upon the outer side 50 of the spout and within said passage with a partition and with ports on opposite sides of said partition.

In testimony whereof I hereunto affix my signature in the presence of two witnesses. 55

PORTER S. HAMRICK.
